ELECTRICAL SIGNAL TRANSLATING APPARATUS

Emile C. Guedon, Audubon, N. J., assignor to
Radio Corporation of America, a corporation
of Delaware

Application April 30, 1938, Serial No. 205,233

4 Claims. (Cl. 179—100.4)

This invention relates to electrical signal translating apparatus, and more particularly to a pick-up device for reproducing sound from a phonograph record.

It is well known that, in phonographs used for the reproduction of sound, there are sources of mechanical vibrations other than those imparted to the reproducing needle by the record, and this is especially true in the case of inexpensive machines. One common source of such vibrations, for example, is the driving motor of the phonograph from which mechanical vibrations are transmitted to the sound translating apparatus and are reproduced thereby as undesired noises. The order of magnitude of such disturbances is usually such that they do not cause appreciable distortion of the sound reproduced from the record, but when reproduction of a record has been completed and the record is being changed while the motor is operating, these disturbances sometimes become quite evident and often fairly annoying.

The primary object of my present invention is to provide improved electrical sound translating apparatus which will be free from the aforementioned objectionable feature.

More particularly, it is an object of my invention to provide improved electrical sound translating apparatus which can easily and automatically be so conditioned during changing of records that no sounds or noises will be reproduced thereby at this time.

Another object of my invention is to provide an improved electrical pick-up device which is adapted to cooperate with a needle gauge of the type disclosed in my copending application, Serial No. 187,935, to be automatically rendered inoperative to reproduce sound when associated with such needle gauge.

Still another object of my invention is to provide improved sound translating apparatus as aforesaid which is simple in construction, inexpensive in cost, easy to manufacture, and highly efficient in use.

In my above-identified copending application, I have disclosed a combined pick-up support and needle gauge upon which the pick-up may be supported to one side of the turntable and which may be used effectively with pick-ups of the top loading type to suitable gauge the needle in the needle socket of the pick-up. According to my present invention, I provide the pick-up with a short-circuiting switch connected across its output terminals and arrange it to coat with a projection on the support when the pick-up is

placed thereon, the said projection serving to automatically close the short-circuiting switch whereby mechanical vibrations originating in the phonograph motor or other sources are prevented from being transmitted through the pick-up to the amplifier and loudspeaker mechanism of the phonograph.

The novel features that I consider characteristic of my invention are set forth with particularity in the appended claims. The invention itself, however, both as to its organization and method of operation, as well as additional objects and advantages thereof, will best be understood from the following description of one embodiment thereof, when read in connection with the accompanying drawing, in which

Figure 1 is an elevational view showing a pick-up device constructed according to my invention in cooperative relation with its support,

Figure 2 is an enlarged, plan view of a pick-up according to my invention, and

Figure 3 is an elevation thereof.

Referring more particularly to the drawing, wherein similar reference characters designate corresponding parts throughout, there is shown, in Fig. 1, a motor board 1 having an opening 3 therein into which is fitted a combined pick-up supporting and needle gauging device of the type disclosed and claimed in my above identified copending application. This device includes, generally, a frame 5 from which depends a needle receptacle 7 adapted to receive used needles, and a pivoted cover 9 which serves to gauge the extent to which a needle 11 will extend from the needle socket of a pick-up, or signal translating device 13. Extending upwardly from the frame 5 are a pair of posts 15 and 17 which serve to locate the pick-up device 13 with respect to the cover or gauge 9, the post 17 being suitably notched at its upper end, as at 19, to receive one edge of a substantially rigid, unitary pick-up arm 21 in the free end of which the pick-up 13 is mounted.

The pick-up device 13 may be of any suitable type and is provided with output terminals 23 and 25 for external connection to suitable amplifying and loudspeaker apparatus (not shown). A switch constituted by a pair of spring blades 27 and 29, the former of which is connected to the output terminal 23 and the latter to the output terminal 25, serves, when closed, to short circuit the pick-up device 13, since this switch is connected in shunt relation thereto. The spring blade 29 is somewhat shorter than the blade 27 and is provided with a downward extension 31.

adapted to be engaged by the spring blade 27 when the latter is moved upwardly a sufficient distance. The blade 27 is also provided with a downward extension 33 which is adapted to be engaged by a projection 35 on the supporting post 17 when the arm 21 and its pick-up 13 are placed upon the supporting posts 15 and 17. The projection or extension 35 is so arranged on the post 17 that, when a predetermined edge of the pick-up arm 21 rests in the notch 19, the spring blade 27 of the switch will have been moved up thereby into contact with the downward extension 31 of the spring blade 29.

The pick-up arm 21 is mounted for pivotal movement relative to a record supporting turntable (not shown) and also relative to the supporting posts 15 and 17, the posts 15-17 being fixedly mounted on the motor board 1 to one side of the turntable. From the foregoing description it will be apparent that, by merely resting the pick-up arm 21 on the supports 15 and 17 in the predetermined relation previously described, the projection 35 will automatically close the switch 27-29 and thereby short circuit the pick-up device 13. Thus, the transmission to the sound reproducing apparatus of vibrations originating in the phonograph motor, the turntable, or any other parts of the apparatus will be entirely avoided while the pick-up arm 21 is in its rest position on the supporting posts 15 and 17.

Although I have shown and described but one embodiment of my invention, it will be apparent to those skilled in the art that many other modifications thereof are possible. I therefore desire that my invention shall not be limited except insofar as is made necessary by the prior art and by the spirit of the appended claims.

I claim as my invention:

1. In combination, a pick-up arm, an electrical signal translating device carried thereby, a normally open switch carried by said device and connected in shunt therewith, said switch being adapted, when closed, to render said device inoperative to translate signals, a support for said arm and said device, and means on said support adapted to close said switch when said device is placed on said support in predetermined relation thereto. 10

2. In combination, a pick-up arm, an electrical signal translating device carried thereby, a normally open switch carried by said device and connected in shunt therewith, said switch being adapted, when closed, to render said device inoperative to translate signals, a support for said arm and said device, and a projection carried by said support, said projection being adapted to close said switch when said device is placed on said support in predetermined relation 20 thereto. 15

3. The invention set forth in claim 2 characterized by the addition of a record supporting member, and characterized further in that said support is fixedly mounted to one side of said 25 member.

4. The invention set forth in claim 2 characterized by the addition of a record supporting member, characterized further in that said pick-up arm is constituted by a substantially 30 rigid member mounted for pivotal movement relative to both said support and said record supporting member, characterized further in that said signal translating device is carried by the free end of said arm, and characterized still further in that said support is fixedly mounted to one side of said record supporting member. 35
